FIG. 5 is a left view thereof;

FIG. 6 is a right view thereof;

FIG. 7 is a top view thereof;

FIG. 8 is a bottom view thereof;

FIG. 9 is a top, front, right side perspective view thereof with the two sections of the data cable disposed in a partially open state;

FIG. 10 is a top, front, right side perspective view thereof with the two sections of the data cable disposed in a partially opened and folded backwards state.

FIG. 11 is an enlarged view of the FIG. 7.

FIG. 12 is a top, front, right side perspective view of the data cable showing a second embodiment of my new design;

FIG. 13 is a bottom, rear, left side perspective view thereof;

FIG. 14 is a front view thereof;

FIG. 15 is a back view thereof;

FIG. 16 is a left view thereof;

FIG. 17 is a right view thereof;

FIG. 18 is a top view thereof;

FIG. 19 is a bottom view thereof;

FIG. 20 is a top, front, right side perspective view thereof with the two sections of the data cable disposed in a partially open state;

(Continued)

FIG. 21 is a top, front, right side perspective view thereof with the two sections of the data cable disposed in a partially opened and folded backwards state;
 FIG. 22 is a top, front, right side perspective view of the data cable showing a third embodiment of my new design;
 FIG. 23 is a bottom, rear, left side perspective view thereof;
 FIG. 24 is a front view thereof;
 FIG. 25 is a back view thereof;
 FIG. 26 is a left view thereof;
 FIG. 27 is a right view thereof;
 FIG. 28 is a top view thereof;
 FIG. 29 is a bottom view thereof;
 FIG. 30 is a top, front, right side perspective view thereof with the two sections of the data cable disposed in a partially open state; and,
 FIG. 31 is a top, front, right side perspective view thereof with the two sections of the data cable disposed in a partially opened and folded backwards state.
 The broken line showing of a data cable is included for the purpose of illustrating portions of the article and forms no part of the claimed design.
